UNITED STATES PATENT OFFICE

150,674

DESIGN FOR A CASING FOR A SPACE HEATER

Aloysius W. Becker, Chicago, Ill., assignor to
Dearborn Stove Company, Chicago, Ill., a cor-
poration of Illinois

Application April 10, 1947, Serial No. 138,274

Term of patent 3½ years

(Cl. D81—10)

To all whom it may concern:

Be it known that I, Aloysius W. Becker, a citizen of the United States and a resident of Chicago, county of Cook, and State of Illinois, have invented a new, original, and ornamental Design for a Casing for a Space Heater, of which the following is a specification, reference being had to the accompanying drawing, forming a part thereof, in which Fig. 1 is a perspective view of a casing for a space heater showing my new design; Fig. 2 is a front view of the same on substantially the scale of Fig. 1; Fig. 3 is a side view thereof on the scale of Fig. 2; and Fig. 4 is a top view of the same.

I claim:

The ornamental design for a casing for a space heater, substantially as shown.

ALOYSIUS W. BECKER.
